SIDEARM CIRCULATING WATER HEATER

Howard C. Reed, Dunkirk, N. Y., assignor to
Sears, Roebuck and Co., Chicago, Ill., a cor-
poration of New York

Application March 2, 1944, Serial No. 524,726

16 Claims. (Cl. 122—223)

1

This invention relates to circulating water heaters, widely known as side arm water heaters.

Objects of my invention are: to provide a circulating water heater such as those for domestic use in which the casing serves as a part of the heat exchange unit; to provide a heater of this character having a casing with a lighter door which may be located selectively in different positions for convenience as different installations may require; to provide a heater of this type constructed essentially from modified conventional steam or hot water radiator sections; to provide a heater of this type having lateral extensions of the tubular formation of each section, serving as fins and as baffles and arranged to increase the heat transfer from the flames and gases of combustion and to minimize the loss of heat to the cover parts of the casing; to provide a novel burner mounting; and, among other things, to provide a lighter door biased to closed position and automatically opening in case of an explosion to thereby preclude or at least minimize damage.

Further objects and advantages of the invention will be apparent as the description proceeds.

The invention will be better understood upon reference to the following description and the accompanying drawings, in which:

Fig. 1 is a perspective view of a side arm circulating water heater constructed in accordance with my invention.

Fig. 2 is a fragmentary elevational view of the lower part of the same with a casing panel removed, taken as indicated by the lines 2—2 of Fig. 1.

Fig. 3 is an elevational view of the water inlet and outlet side of the heater.

Fig. 4 is a top plan view of the same.

Fig. 5 is a full height elevational view, partly in section, similar to Fig. 2 but including a portion of the lighter door panel.

Fig. 6 is a sectional view taken as indicated by the line 6—6 in Figs. 5 and 7.

Fig. 7 is a sectional view taken as indicated by the line 7—7 in Figs. 3 and 6.

Figs. 8, 9 and 10 are plan sectional views taken as indicated by the lines 8—8, 9—9 and 10—10 in Fig. 6.

Fig. 11 is an enlarged fragmentary sectional view taken as indicated by the line 11—11 in Fig. 3.

Referring now more particularly to the drawings, I have shown generally at 20 a side arm circulating water heater constructed in accordance with my invention. It may be made of any

2

suitable materials, such, for example, as cast iron. In the development of this heater I have made use of conventional steam or hot water radiator sections and have modified them so that, thus modified, they serve as a side arm water heater. The modifications together with certain other details will now be described.

The conventional side arm water heater is provided with a heat exchange unit surrounded by a casing which forms no part of the heat exchange means. In accordance with my invention, the casing is incorporated in the heat exchange unit and thus I utilize heat which heretofore was lost. To this end the device comprises casing sections 22 and 23 having tubular formations 24 and 25, respectively, the spaces between the tubes being, however, closed as shown at 26. The casing also includes a flue cover top or crown 27 and vertical panels 28 and 29. The tubular formation of each casing section is preferably marginally inset from the longitudinal edges 32, top edge 34 and bottom edge 36, the longitudinal and bottom edges being preferably reinforced as shown at 38 and additional reinforcement being provided at 40 between the bottom of the section and the lower part of the tubular formation. One of these sections has the usual water inlet and outlet openings 42 and 44 at its outer side, and the other section is completely closed at its outer side. Except for these differences, these two casing sections are identical and may be made from the same mold, the mold being provided with cores when the section having the openings 42 and 44 therein is to be cast.

Each of the casing sections 22 and 23 of the heat exchange unit has top and bottom openings 46 and 48 in line with the openings 42 and 44, respectively, and may be joined together or with one or more intervening heat exchange sections 50 as by push nipples 52. In the illustrated embodiment of the invention, a single intervening heat exchange section appears. The intervening section 50 has a tubular formation 54 like those of the casing sections and suitably spaced therefrom when assembled therewith.

The inner side of each of the casing sections 22 and 23 is provided with plate baffles 56 extending substantially the full width thereof. The free longitudinal edges 60 of the baffles 56 are substantially spaced from the intervening tubular formation 54. Alternating with and disposed adjacent the end portions of the plate baffles 56 are relatively short baffles such as lugs 62.

The intervening section 50 has pairs of relatively short baffles such as lugs 66, each prefera-

bly of generally dovetail formation and coplanar with the respective plate baffles 56 on the casing sections 22 and 23. The space 67 between the baffle lugs 62 and 66 of each pair is free, permitting the passage of the gases of combustion between and among the tubes of the tubular formations.

The intermediate tubular section 50 is provided with plate baffles 68 which alternate with the pairs of lug baffles 62 and extend substantially the full width and about each tube of the section. The plate baffles 68 on the intermediate section 50 are arranged to be coplanar with the lug baffles 62 on the casing sections 22 and 23, and the plate baffles 56 on the casing sections are arranged to be coplanar with the lug baffles 66 on the intermediate section 50. It will be noted that the plate baffles are staggered on the mutually facing portions of the sections to cause the gases adjacent the tubular formations to have sinuous flow upward to thereby promote maximum heat transfer from the gases to the tubular formations. The passage area throughout the entire rise is relatively large in view of the fact that the lug baffles of each section cooperating with the plate baffles on the adjacent section are relatively short and the vertical portions of the tubular part 54 of the intermediate section 50 are openly spaced apart as shown at 67^a.

The vertical spacing between the baffles is progressively reduced upward to the lug baffles 62 disposed in proximity to the upper part of the heat exchange unit, and from those baffles upward the baffle spacing is relatively increased. No plate baffle is provided on the intermediate section 50 in cooperation with the uppermost lug baffles 62 on the casing sections 22 and 23. Instead, a baffle 72 similar to the plate baffles 68 referred to above is provided, extending from opposite sides of the upper water passage hub 73 on the intermediate section. Somewhat above the baffle 72, coplanar plate baffles 74 extend from opposite sides of the upper water passage hubs 75 on the respective casing sections.

The respective end edges of all of the baffles are preferably substantially coplanar for disposition adjacent the respective cover panels 28 and 29 (Figs. 8 and 10) and the various baffles in each plane are quite close together, so as to substantially block rising movement of the gases adjacent the cover panels and thus minimize scrubbing action of the gases on and consequently heat transfer therefrom to the cover panels. Moreover, because of this construction pockets are formed adjacent said panels, at the under sides of said baffles, causing the gases in such pockets to substantially stagnate and function as insulating media further reducing heat loss to the panels.

The inclination of the mutually facing edges 16 of each pair of lug baffles augments the area of rising flow of the gases and minimizes turbulence.

The cover panels 28 and 29 may be cast or otherwise provided with means (not shown) for retaining insulating material 80, such as asbestos sheeting. The insulation may be disposed between elongated ribs 84 cast on each cover panel, said ribs having a pair of eyes 86 at the upper ends thereof and another pair of eyes 88 near the bottoms thereof. The ribs 84 are adapted to lie between and engage the inner surfaces 89 of the casing sections and, when the cover panel is in assembly therewith, the eyes 86 are in register with openings 90 formed in the upper ends of

the casing sections and also in register with eyes 94 formed on the top 27. The parts may be assembled by registering the eyes and holes referred to and slipping pins or screws 95 therethrough.

The other set of eyes 88 of each panel is adapted to register with holes formed in bosses 96 on the associated flanges 38 of the casing sections, and the parts may be secured together by means of pins or screws 98.

The cover panels differ only in that one (28) is imperforate and the other (29) has a door opening 100 which is preferably of key-hole form, with a lower narrow portion 102 and an upper wide portion 104. This opening affords access to the burner for lighting, as will appear.

Associated with the cover panel 29 is a door 106 of generally T shape, with a narrow part 108 adapted to cover the narrow portion 102 of the opening from the outside and with a wide part 110 adapted to cover the wide portion 104 of the opening from the inside. The wide portion of the door is offset transversely from the narrow portion thereof and, on the inner side, is provided with eyes 112 adapted to register with the pin-receiving eyes 88 of the associated cover panel 29 and the openings in the bosses 96 of the associated casing sections 22 and 23. One of the pins or screws 98 extending through the three parts just mentioned fixedly secures the panel 29 to the casing sections and also pivotally mounts the door relative thereto. The door may be inserted into position from the inner side of the panel by passing the narrow part of the door outward through the wide portion of the opening until the respective screw holes are in register. The door may be provided with a suitable handle 116.

The four screws referred to above are the only fastening means necessary to completely assemble the heating unit with the remainder of the casing. The device is so compact that less shipping space is occupied if it is completely assembled than if knocked down.

When it is received by the customer, he may find that the particular installation available to him requires the lighter door to be located on the side opposite to that in which it is located when he received the device. In such event it would consume but a minute or two to interchange the cover panels and thus locate the lighter door in a convenient position.

In the illustrated embodiment of the invention the general form of the device in cross section is rectangular, and accordingly I have designed a burner 120 of corresponding form. The burner has an opening 121 in the bottom thereof to receive a fuel mixing throat or tube 122 which will project below the casing. The burner ports 123 are designed to furnish flames directly under the bottoms of the tubular formations. The ports are arranged marginally in the form of a hollow rectangle, opposite sides 124 of which are disposed substantially under the inner bottom portions 125 of the tubular formations 24 and 25 and the water inlet hubs 126 of the casing sections 22 and 23. Within the hollow rectangle, the ports are in a generally cruciform arrangement as indicated at 127 so as to underlie the similarly shaped bottom 128 of the tubular formation 54 and the water inlet passage hubs 129 on the intermediate section 50. The central area 130 of the cross is imperforate in order to serve as a baffle for the gas rising from the mixing tube 122 so that the same

may be spread generally uniformly to the various ports.

For supporting the burner, there are cast at the inner side of the bottom of each casing section 22, 23, pairs of spaced upper and lower lugs 131 between which projections 132 on the sides of the burner are adapted to be disposed. This is readily accomplished when one of the cover panels 28, 29 is off by simply sliding the projections in place. The ends 133 of the burner 120 have projections 134 which engage lugs 136 on the inner faces of the cover panels, whereby to center the burner relative to the heat exchange unit. By providing lugs on the cover panels as well as on the burner, breakage such as would be likely to occur if relatively long lugs were employed on the burner alone or on the cover panels alone is avoided.

It will be noticed that when it is desired to light the burner it is an easy matter for the attendant to grasp the handle 116 and raise the door 106 against the action of gravity and then insert a match through the door opening 100 to the burner, and that the door, when left alone, will lie by gravity in closed position. In the event of an explosion, the door will yield readily to the increased pressure and allow the compressed gases of combustion to escape readily, thus minimizing or obviating damage to the parts of the device.

Various modifications coming within the spirit of my invention may suggest themselves to those skilled in the art, and hence I do not wish to be limited to the specific form shown or uses mentioned, except to the extent indicated in the appended claims, which are to be interpreted as broadly as the state of the art will permit.

I claim:

1. A side arm circulating water heater comprising a heat exchange unit, a casing therefor including a removable panel, a burner, and interengaging means on said casing and burner enabling said burner to be supported in operative position when said panel is removed, and to be slipped out of and into said position in the absence of said panel, and means on said panel operative, when said panel is restored to the remainder of the casing, to positively retain said burner in supported position.

2. A side arm circulating water heater, comprising a heat exchange unit, a casing therefor having four vertical walls, a flue crown embracing the upper ends of said walls, and a fastening disposed at the inner face of each of two opposite walls of said casing and extending widthwise thereof and passing through marginal portions of said opposite walls, the other two walls and said crown, whereby the four walls and crown are held in assembly by two fastenings disposed substantially out of the path of rising gases.

3. A side arm circulating water heater comprising a heat exchange unit, a casing therefor, a burner, means on said casing for supporting said burner in cooperative relation to the heat exchange unit, said casing including a plurality of separable panels, one of which has a burner lighter opening, and means interchangeably securing said panels in assembly with the remainder of the casing, whereby said panels may be interchangeably positioned to locate said opening at the most convenient position for the user in any given installation.

4. A side arm circulating water heater comprising a heat exchange unit, a casing therefor, a burner, means on said casing for supporting said burner in cooperative relation to said heat ex-

change unit, said casing including a removable panel having a burner lighter opening, a door for said opening, and means for fastening said panel to the remainder of the casing, said fastening means comprising a pin serving as a pivot for said door.

5. A side arm circulating water heater comprising a casing including spaced heat exchange sections, a heat exchange section between said casing heat exchange sections, main baffles on and extending substantially the full widths of the mutually facing portions of said sections, the baffles on each portion alternating with those on the mutually facing portions, and auxiliary baffles on each of said portions alternating with and disposed only adjacent the ends of said main baffles, said baffles being arranged to stagnate gases of combustion entering the spaces therebetween at the ends of said main baffles, whereby to minimize heat transfer from the remaining gases to the remaining walls of said casing.

6. A side arm circulating water heater comprising a heat exchange unit including two opposite one-piece heat exchange sections, each section having a formation adapted to contain water, means establishing communication between said formations, one of said formations having inlet and outlet openings for connection with a water tank, two additional one-piece panels connected with said heat exchange sections and forming therewith an enclosure extending below and above said formations, said enclosure being open at the bottom to accommodate a source of heat and open at the top to provide a flue.

7. A side arm circulating water heater comprising a heat exchange unit including two opposite one-piece heat exchange sections, each section having a formation adapted to contain water, means establishing communication between said formations, one of said formations having inlet and outlet openings for connection with a water tank and two additional one piece panels connected with said heat exchange sections and forming with said sections an enclosure extending below and above said formations, said enclosure being open at the bottom to accommodate a source of heat and open at the top to provide a flue, said communication-establishing means comprising a heat exchange formation adapted to contain water, the last-mentioned formation being disposed within said enclosure.

8. A side arm circulating water heater comprising a heat exchange unit including two opposite one-piece heat exchange sections, each section having a formation adapted to contain water, means establishing communication between said formations, one of said formations having inlet and outlet openings for connection with a water tank, two additional one-piece panels connected with said heat exchange sections and forming therewith an enclosure extending below and above said formations, said enclosure being open at the bottom to accommodate a source of heat and open at the top to provide a flue, a fluid fuel burner, and cooperating means on said burner and on said enclosure below said formations, for supporting said burner.

9. A side arm circulating water heater comprising a heat exchange unit, a casing therefor adapted to accommodate a burner in cooperative relation to said heat exchange unit, said casing including a panel having a burner lighter opening, a door for said opening, a means for fastening said panel to the remainder of the casing, said

fastening means comprising a pin serving as a pivot for said door.

10. A side arm circulating water heater comprising a casing including spaced heat exchange sections having heat exchange tubular formations, a heat exchange tubular formation between said casing heat exchange sections, each of said formations comprising a plurality of horizontally spaced tubular elements, the spaces between said elements on said casing sections being closed, the spaces between said elements on the intermediate formation being open, main baffles on and extending substantially the full width of the mutually facing portions of said sections and intermediate formation, the baffles on each portion alternating with those on the mutually facing portion, and auxiliary baffles on each of said portions alternating with and disposed only adjacent the ends of said main baffles, said baffles being arranged to stagnate gases of combustion entering the spaces therebetween at the ends of said main baffles, whereby to minimize heat transfer from the remaining gases to walls of said casing other than said sections.

11. A side arm circulating water heater comprising a casing including spaced heat exchange sections having heat exchange tubular formations, an intermediate heat exchange formation, and means cooperating with said casing sections for substantially enclosing said intermediate formation, each of said sections having a tubular formation, means establishing communication between all of said formations, each of said formations comprising a plurality of tubes, the spaces between said tubes of each casing section formation being closed, the spaces between said tubes of the intermediate formation being open.

12. A side arm circulating water heater comprising a heat exchange unit including heat exchange sections, each having a vertically extending formation adapted to contain water, means establishing communication between said formations, one of said formations having inlet and outlet openings for connection with a water tank, means connected with said sections and forming therewith an enclosure open at the bottom to accommodate a source of heat and open at the top to provide a flue, means for causing rising gases to scrub said formations, and means for substantially stagnating the gases adjacent the portions of said enclosure between said sections.

13. A side arm circulating water heater comprising a heat exchange unit including heat exchange sections, each having a vertically extending formation adapted to contain water, means establishing communication between said formations, one of said formations having inlet and outlet openings for connection with a water tank, means connected with said sections and forming therewith an enclosure open at the bot-

tom to accommodate a source of heat and open at the top to provide a flue, and a vertical series of baffles on each formation within said enclosure, said baffles in each series being progressively closer together from the bottoms to a level adjacent the tops of said formations.

14. A side arm circulating water heater comprising a heat exchange unit including heat exchange sections, each having a vertically extending formation adapted to contain water, means establishing communication between said formations, one of said formations having inlet and outlet openings for connection with a water tank, means connected with said sections and forming therewith an enclosure open at the bottom to accommodate a source of heat and open at the top to provide a flue, and a vertical series of baffles on each formation within said enclosure, said baffles in each series being progressively closer together from the bottoms to a level adjacent the tops of said formations and being spaced farther apart from said level upward.

15. A side arm circulating water heater comprising a heat exchange unit including heat exchange sections, each section having a vertically extending formation adapted to contain water, means establishing communication between said formations, one of said formations having inlet and outlet openings for connection with a water tank, means connected with said sections and forming therewith an enclosure open at the bottom to accommodate a source of heat and open at the top to provide a flue, and a vertical series of baffles on each of the mutually facing portions of said formations within said enclosure, said baffles in each series alternating with those in the mutually facing series and being progressively closer together from the bottoms to a level adjacent the tops of said formations.

16. A side arm circulating water heater comprising a heat exchange unit including heat exchange sections, each section having a vertically extending formation adapted to contain water, means establishing communication between said formations, one of said formations having inlet and outlet openings for connection with a water tank, means connected with said sections and forming therewith an enclosure open at the bottom to accommodate a source of heat and open at the top to provide a flue, and a vertical series of baffles on each formation within said enclosure, said baffles in each series being progressively closer together from the bottoms to a level adjacent the tops of said formations, said baffles being formed to provide a substantial path for the flow of the rising gases in contact with said formations and being formed adjacent the remainder of said enclosure to provide insulating pockets in which portions of the rising gases are adapted to stagnate.

HOWARD C. REED.
